UNITED STATES PATENT OFFICE.

WILLIAM J. DAVIS, OF CHICAGO, ILLINOIS.

TEMPERATURE-CHANGING APPARATUS.

1,272,232.

Specification of Letters Patent.

Patented July 9, 1918.

Application filed July 23, 1917. Serial No. 182,116.

To all whom it may concern:

Be it known that I, WILLIAM J. DAVIS, a citizen of the United States, and a resident of Chicago, in the county of Cook and State 5 of Illinois, have invented certain new and useful Improvements in Temperature-Changing Apparatus, of which the following is a full, clear, and exact specification.

My invention is concerned with temperature-changing apparatus of the character in which a fluid to be treated, *i. e.*, heated or cooled, is run through a tortuous passage surrounded by another tortuous passage through which is run a hotter or colder, as 15 the case may be, treating fluid, so that the heat may be transferred from the hotter to the cooler fluid, and vice versa, the apparatus being more especially designed for use in pasteurizing outfits for milk, etc., where 20 the same form of apparatus, supplied with hot water, can be used to heat milk to a pasteurizing temperature or, supplied with cold water or brine, used for cooling it, after pasteurizing and before bottling it, and it is 25 designed to improve upon such apparatus as has been heretofore used by using to a greater extent than has been possible heretofore all the thermal units in the heating fluid.

30 In carrying out my invention in its preferred form, the tortuous passage for the treating fluid is constructed so as to be readily surrounded with a jacket spaced therefrom so as to form a dead-air space from 35 which the air can be exhausted to form a vacuum about said passage to prevent radiation and loss or gain of heat from the outer surface thereof. To the same end of conserving heat or cold, I secure a larger contact surface for the fluid to be treated by 40 running it through a plurality of small tubes grouped in a single large tube through which the treating fluid flows.

Another feature of my novel apparatus is 45 the employment of a novel distributing guide for the fluid to be treated, at the turns, when I employ the plurality of small pipes in a group, so that all the pipes in the same group carry their proportion of the milk. 50 Still another feature resides in the employment of one or more vent pipes leading from enlargements in the passage for the fluid to be treated to the atmosphere, so that hot

vapors and odors can escape therefrom during the process. 55

To illustrate my invention, I annex hereto three sheets of drawings, in which the same reference characters are used to designate identical parts in all the figures, of which,—

Figure 1 is a side elevation of a unit containing my invention; 60

Fig. 2 is a central longitudinal vertical section through the same;

Fig. 3 is an end elevation of one end, on a larger scale; 65

Fig. 4 is a view of the same end, but with the door and connecting elbows swung open;

Fig. 5 is a view similar to Fig. 3, but of the other end;

Fig. 6 is a view of the same end, but with the doors swung open; 70

Fig. 7 is a detail, in section, on the line 7—7 of Fig. 3;

Figs. 8 and 9 are details, in section, on the lines 8—8 and 9—9, of Fig. 2, but on the 75 same scale as Figs. 3 to 7, inclusive;

Fig. 10 is a detail, in section, on the line 10—10 of Fig. 7;

Fig. 11 is a top plan view of the end seen in Fig. 7; and 80

Fig. 12 is a detail, in section, on the lines 12—12 of Fig. 7.

In carrying out my invention in its preferred form, I employ a pair of heads 20 and 21, which are connected by a pair of 85 similar jackets 22 and 23. The jackets 22 and 23 are preferably elongated hollow castings, which may be slightly tapered as shown, and are provided at their ends with heads 24 and 25, which may be integral 90 therewith, or not, as desired. Formed in each head are a pair of circular apertures 26, through which are passed by a snug fit the ends of the large treating-fluid pipes 27, a liquid-tight joint being formed preferably 95 by the packing 28 and the packing rings 29 screwed into the enlarged outer portion of the aperture 26. The head 24 is provided at its upper end with a recess 30 into which the pipe 27 opens, and connected with the upper 100 part of this recess in any suitable manner is the pipe 31 for the exit of the treating fluid, assuming that the said fluid enters through the pipe 32 in the lower head 24 and emerges from the pipe 31 in the upper head. As 105 shown in Figs. 2 and 7, there are four of the

pipes 27, the first and second, and third and fourth, respectively, counting from the top, being connected in the head 25, while the second and third are connected in the head 24, the connections being mainly formed by the recesses 33 formed in the faces of the heads 24 and 25. They are also connected by the passages formed by the apertures 34 in the heads 20 and 21, which register with the 10 passages 35 formed in the generally semi-spherical doors 36, the details of which will be explained more fully at a later point. The pipe 32 opens into a recess 37 in the lower end of the head 24, corresponding to 15 the recess 30 in the upper end thereof. With the construction thus far explained, it will be apparent that there is formed a tortuous passage for the heating fluid entering through the pipe 32, passing through the 20 recess 37 into the lowermost of the pipes 27, through said pipe to the lower recess in the head 25, through said recess and the passages 34 and 35 to the next to the bottom pipe 27, through which it returns to the head 24, and through the same passages enters 25 the next to the top pipe 27, through which it passes to the head 25, and through the same passages reaches that end of the uppermost pipe 27 through which it flows to the 30 recess 30 and is discharged from the pipe 31.

Referring now to the passages for the milk, or other liquid to be treated, it is delivered by a suitable pipe, detachably connected to the elbow 38, which has the flanged face 39, preferably ground, and held tightly against the outer, preferably ground, face of the adjacent upper portion of the head 20. As a convenient method of mounting this and the similar elbow 40 at the bottom, I employ the yoke 41, best seen in Fig. 11, which is hinged at 42 to the ears 43, which are rigidly secured to the head portion 24 of the casing 22. The yoke 41 is in turn hinged at 44 to ears 45 projecting outward from the 45 elbows 38 and 40, and the forked end 46 of the yoke is passed over the bolt 47 hinged at 48 to the ears 49 secured on the opposite side of the head 24 from the ears 43. The wing nut 50 coöperating with the threaded end 50 of the bolt 47 furnishes means for drawing the ground faces of the elbows tightly against the coöperating ground faces of the head 20, and the packing annulus 51 mounted in the annular channel 52 in the face of 55 the flange 39 also serves to make a liquid-tight joint.

The tortuous passages for the liquid to be treated are formed by the plurality of small pipes 53 grouped inside of the 60 pipes 27, preferably in the manner best shown in Figs. 8 and 9, and these pipes have their ends secured by a liquid-tight joint in the disk 54, which is inserted by a liquid-tight joint in the circu-

lar aperture 55 in the head 20; a liquid-tight 65 joint, capable of expansion, preferably being formed by making an annular recess in the outer face of the head 20 around the aperture 55 so as to receive the annular packing 56 and the threaded ring 57 by which the 70 packing is secured in place. All these pipes 53 are secured at their ends in the heads 20 and 21 in the same manner, and it is obvious that the plurality of small passages in the pipes 53 must be connected at the alternate 75 ends through the doors 36, of which there will be one at each end where two sets of the pipes 53 are to be connected. These doors 36 are preferably castings, and are preferably provided adjacent their outer faces with 80 the cored-out hollows 58, corresponding to the general shape of the outer faces of the doors, and serving as vacuum spaces to prevent the escape of heat through said doors. The connecting passages 35 have already 85 been noted, and the faces of the doors co-operating with the ground faces of the heads 20 and 21 are likewise preferably ground and provided with the elliptical channels 59 for a packing, and with the intermediate 90 channel 60 for the same purpose, the two sets of channels being necessary to form the liquid-tight joints separating the passages for the heating fluid and the milk. To furnish an indication in case of a leak past 95 either of these channels 59 and 60, I place between them a straight channel 61 extending entirely across the door, so that if the milk or the water is leaking past its packing channel 60 or 59, it will run out at the ends 100 of the channel 61, indicating the leak and which channel it is in, so it can be remedied. The doors are preferably supported and clamped in position by the connections best shown in Figs. 7 and 10, where it will be 105 seen that each of said doors has at its top and bottom a hand bolt 62 screwed through a suitable aperture in the yoke 63 and provided with the ball at its inner end coöperating with the socket formed on the outer 110 face of the door. The yoke 63 is hinged at 64 to the ears 65 secured to the heads 24 and 25, and its other end is provided with a suitable bearing surface 66 over which passes one of the two coöperating surfaces 115 67 formed on the locking handle 68 journaled at both ends in the brackets 68 secured on the heads 24 and 25. Obviously, when the door is to be opened to clean the device, the handle 68 is swung away, after 120 which the doors can be swung open by swinging the yokes 63 on the hinges 64.

To insure all the pipes 33 in the uppermost set being uniformly filled, I preferably locate in the elbow 38 a quadrant-shaped 125 guide-piece 69, which is shaped as seen in Figs. 6 and 11, and in its general shape is adapted to be slipped into the passage

through the elbow 38 from its vertical opening when the elbow is swung out. The guide piece 69 is provided with a central passage 70 adapted to coöperate with the 5 central pipe 53, and in its outer face is provided with a series of channels 71 adapted to coöperate with the outer pipes 53. With this spreading device, it will be obvious that the milk flowing vertically down into the 10 top of the elbow will be distributed substantially uniformly through the entire set of pipes 53, whereas if this guide or spreader was not employed, it would tend to fill up the lower pipes 53, leaving the upper ones 15 empty. For the same purpose, I provide in each of the doors a similar quadrant guide 72, best seen in Figs. 7 and 12, and to prevent the same being removed and damaged in cleaning, I preferably hinge it near 20 to the open side of the door by the pin 73. In use, the quadrant occupies the position shown in Fig. 7, but when the door is opened for cleansing purposes, it can be swung up outward to give free access to the inside of 25 the door, and also to facilitate the cleaning of the circular passages 74 therethrough, which correspond with the passages 70 and 71 of the elbow-guide 69.

It will also be evident that the milk flowing from the pipes 53 into the open upper portion of the door will not completely fill said open upper portion, which has a much greater cross-sectional area than the pipes, and in this enlargement of the passage, it 35 is possible for the vapors arising from the heated milk to expand and separate therefrom, and to permit them to escape to the air, thus removing some of the surplus heat and possible odors, I provide the vent pipe 40 75 screwed through the side of the door and connected with a vertical tube or extension 76, which is preferably made of glass. If the proper amount of milk is flowing through the pipes 53, the milk does not stand 45 in the pipe 76, but if the milk should be fed to the apparatus too rapidly, it will stand in the pipe 76, and possibly overflow, thus warning the operator to cut down the supply delivered to the apparatus. If desired, 50 I may place an outwardly opening check-valve in the tube 76 to prevent the possibility of sucking in cold or hot air from the outside.

To prevent more than the proper portion 55 of the heating fluid passing directly from the end of the first tube 27 to the second one, and from the second to the third, etc., and to compel the desired proportion to go through the passages 35 in the doors, I place 60 the rib 77 transversely of the recess 33 between each of the coöoperating ends of said pipes 27, thereby narrowing the direct passage for the hot water and compelling a proper proportion to flow through the pas-

sage 35. Each of the casings 22 and 23 are 65 shown as provided with check-valves 78, to which air pumps are to be applied, for exhausting the air therefrom so as to maintain a vacuum about the pipes 27. Similar valves may be connected to the doors 36 to exhaust 70 the air from the spaces 58.

While I have shown and described my invention as embodied in the form which I at present consider best adapted to carry out its purposes, it will be understood that 75 it is capable of modifications, and that I do not desire to be limited in the interpretation of the following claims except as may be necessitated by the state of the prior art.

What I claim as new, and desire to secure 80 by Letters Patent of the United States, is:

1. In a device of the class described, the combination with a pair of heads, of a plurality of large tubes connecting said heads, connected to each other at alternate ends 85 through said heads, a series of smaller tubes inclosed within the larger ones and passing through said heads, doors secured to the outer faces of the heads containing connecting passages for said smaller tubes at alternate ends, and a quadrant-shaped guide containing curved passages coöperating with the lower set of small tubes opening into the connecting passages in the doors. 90

2. In a device of the class described, the 95 combination with a pair of heads, of a plurality of large tubes connecting said heads, connected to each other at alternate ends, a series of smaller tubes inclosed within the larger ones and passing through said heads, 100 doors secured to the outer faces of the heads containing connecting passages for said smaller tubes at alternate ends, an elbow coöperating with the outer face of the head and the smaller tubes, a yoke having the 105 elbow pivoted in the center thereof hinged to one side of the head, and means at the other end of the yoke for forcing it toward the head to clamp the elbow to the head.

3. In a device of the class described, the 110 combination with a pair of heads, of a plurality of large tubes connecting said heads, connected to each other at alternate ends, a series of smaller tubes inclosed within the larger ones and passing through said heads, 115 doors secured to the outer faces of the heads containing connecting passages for said smaller tubes at alternate ends, and a quadrant-shaped member coöperating with the entrance end of a series of the smaller 120 tubes having a plurality of passages therethrough corresponding to the tubes which form a continuation thereof.

4. In a device of the class described, the combination with a pair of heads, of the 125 large heating-fluid pipes connecting said heads, smaller pipes therein for heating the fluid to be treated, doors coöperating with

said heads and having two sets of passages therethrough to connect the adjacent ends of the two sets of pipes at alternate ends to form two sets of tortuous passages for the 5 heating fluid and the fluid to be treated; packing channels and packing therein in the opposed faces of the heads and doors surrounding the openings therein for the two sets of passages, and transverse channels be-

tween the channels for the two sets of passages to disclose leaks, substantially as described.

In witness whereof, I have hereunto set my hand and affixed my seal, this 21st day of July, A. D. 1917.

WILLIAM J. DAVIS. [L.s.]

Witness:
JOHN HOWARD McELROY.
